UNITED STATES PATENT OFFICE.

ALBERT C. FRIESEKE, OF FLORALBLUFF, FLORIDA.

HYDRAULIC OIL-TANK.

SPECIFICATION forming part of Letters Patent No. 727,779, dated May 12, 1903.

Application filed October 31, 1902. Serial No. 129,519. (No model.)

To all whom it may concern:

Be it known that I, ALBERT C. FRIESEKE, a citizen of the United States, residing at Floralbluff, county of Duval, and State of Florida, 5 have invented a certain new and useful Improvement in Hydraulic Oil-Tanks, of which the following is a specification.

My invention relates to a new and useful improvement in hydraulic oil-tanks, and has 10 for its object to provide a tank and mechanism connected therewith, so that the oil may be drawn from the barrel into the tank hydraulically without exposing the oil to the air, and I also provide means for drawing the 15 oil from the tank by one pressure.

Other minor objects will be set forth more clearly in the specification.

With these ends in view this invention consists in the details of construction and combination of elements hereinafter set forth and then specifically designated by the claims. 20

In order that those skilled in the art to which this invention appertains may understand how to make and use the same, the construction and operation will now be described in detail, referring to the accompanying drawings, forming a part of this specification, in which—

Figure 1 is a vertical longitudinal section 30 through my improved oil-tank, showing the parts in the position they would assume when oil is being drawn from the barrel into the tank; Fig. 2, a vertical longitudinal section through the tank, showing the same entirely 35 filled with water; and Fig. 3, a sectional view of the plug to be inserted in the top of the tank.

A represents the oil-tank, which is entirely closed except for the small opening A' through 40 the upper end thereof, which opening is normally closed by a plug.

B is a water-supply pipe extending from a water-main, elevated cistern, or other source of supply and extending into the tank near 45 the lower end thereof.

C is an exhaust-water pipe leading from the interior of the tank near its lower end to a sewer or other drain.

D is a pipe leading upward from the upper 50 end of the tank into a measuring vessel E.

Interposed in the pipe D is a two-way valve D', from which the spout F leads.

G is a rod secured at its lower end to the bottom of the tank.

G' is a float the specific gravity of which is 55 such that it will float upon water, but not upon oil. Extending through and secured to the center of this float is a sleeve G², which surrounds and slides upon the rod G, whereby the float is guided.

The supply-pipe B is provided with a valve B', the valve-stem of which is connected, by means of a rod B³, with a lever D², which lever is secured to the stem of the two-way valve D'. 60

The outlet-pipe C is provided with an opening through its upper side upon the interior of the tank, and this opening is adapted to be controlled by a flap-valve C', to which a float C² is attached, so that this valve will 70 remain normally open.

C³ is a valve located in the pipe C outside of the tank, the valve-stem C⁴ of which extends up to the upper end of the tank and is adapted to be turned by means of the handle C⁵. 75

H is a screw-plug adapted to be inserted in the opening A', so as to make the tank air-tight.

To fill the tank, the screw-plug H is removed, the valve C³ is closed, and the valve B' opened. Water will then enter the tank, and as the water rises in the tank the float G' will rise with it, and when the sleeve G² protrudes through the opening A' the valve 80 B' is closed. Then one end of the siphon-pipe I is inserted in the opening A', so as to make an air-tight connection with the tank, and the other end of the pipe I is inserted in the barrel of oil. Then the valve C³ is opened, 85 and the water will flow out of the tank through the pipe C, and in so doing will draw the oil from the barrel into the tank, and as the float G' will follow the water-line downward when it reaches nearly to the bottom of the tank it 90 will strike the flap-valve C' and force the same downward, thus cutting off the outflow of the water, and thereby prevent the possibility of any oil being wasted through the pipe C. Then by closing the valve C³, re- 95

100

moving the pipe I, and inserting the screw-plug H the tank is filled with oil and has not been and is not exposed to the air, so that no evaporation will ensue.

5 The plug of the valve D' is provided with a straight passage D³ and also with a passage D⁴ at right angles to the passage D³, extending from one side of the plug to the passage D³. The valves D' and B' by being connected together by the connection B³ may be operated by one handle J, and when the valve D' is turned so that the passage D³ is vertical and the opening to the spout F is closed then the valve B' will be open, and the water entering the tank underneath the oil will thus force the oil upward into the measuring vessel E, and when sufficient oil has been admitted to the vessel E the plug of the valve D' is given one-quarter of a revolution, which 15 will bring it in the position shown in Fig. 2, closing the valve B' and allowing the oil to flow from the vessel E through the spout F into the proper receptacle. Thus as the oil is drawn from the tank the water will gradually rise in the same, carrying the float G' upward with it until the sleeve G² will protrude through the opening A' when the plug is removed, and thus indicate that the supply of oil in the tank has been exhausted. Of 25 course it will be understood that the plug is only removed temporarily to ascertain if the oil is nearly exhausted, and when this plug is removed no pressure will be upon the oil, as the water will be shut off, and when the 30 plug is reinserted it will press the float and sleeve downward.

L is a tapering adjustable nozzle adapted to fit over the lower end of the spout F, and this nozzle carries a spring L', the free end of 40 which is in partial contact with the spout, so that this nozzle may be raised or lowered to suit different heights of receptacles, but always remain upon the spout.

The advantage of my improved tank is that 45 the contents are hermetically sealed, rendering waste from evaporation and accidents resulting therefrom impossible, the oil not being exposed to air while transferring it from the barrel to the tank, and even while transferring oil from the measuring vessel to the 50 purchaser's receptacle it is never exposed to the outer air.

Another advantage of my improved tank is that no space is left in the tank in which 55 gas may form, the tank being always filled with either water or oil, or both, and thus many accidents are avoided, which result from partially-filled tanks of inflammable fluid in which a large gas-space is formed and the gas 60 may become ignited by various causes.

Another advantage of my tank is that no labor is required to operate the same, as the tank is filled and emptied hydraulically, and therefore no pumping is required, and by utilizing 65 this water-power I am enabled to simplify the construction greatly, and by forcing

the oil upward into the measuring vessel by means of water I am enabled to always make an accurate measurement and must always be uniform, which fact is evident to the eye 70 of the purchaser.

Having thus fully described my invention, what I claim as new and useful is—

1. In an oil-tank, a reservoir provided with a small opening through its upper end, a removable plug adapted to normally close said opening, a water-supply pipe entering the reservoir near its lower end, a valve located in said pipe, an outlet-pipe extending through the lower end of the reservoir, said pipe provided with an opening into the interior of the reservoir, a float-valve adapted to control said opening, a valve located in the outlet-pipe outside of the reservoir, a float of such specific gravity as to float in water and not in oil 80 arranged upon the interior of the tank and guided vertically therein, a pipe extending upward from the upper end of the reservoir, a measuring vessel located upon the upper end of said pipe, a two-way valve located 90 within said pipe, said two-way valve being connected to the valve in the inlet-pipe so that the two valves will operate together, a spout extending from the two-way valve, and a siphon-pipe, one end of which is adapted to 95 be inserted in the opening in the reservoir, and the other end in an oil-barrel, as and for the purpose specified.

2. In a device of the character described, a tank, a water-supply pipe entering the lower 100 end of said tank, a water-outlet pipe extending from the lower end of said tank, valves located within these pipes, an oil-outlet pipe extending from the upper end of the tank, a siphon-pipe by which the upper end of the 105 tank is connected to an oil-barrel, a float guided vertically within the tank, said float being of such specific gravity as to float upon water and not upon oil, a valve arranged upon the inner end of the water-outlet pipe, 110 said valve consisting of a flap normally open and adapted to be closed by the weight of the float, as and for the purpose specified.

3. In combination in a device of the character described, a tank provided with a water 115 inlet and outlet at its lower end, and an oil-outlet at its upper end through which the oil is expelled from the tank hydraulically, an opening through the upper end of the tank 120 through which the oil is drawn hydraulically into the tank, a plug normally closing said opening, a valve located in the water-inlet pipe, and a valve located in the oil-outlet pipe, a connection between the valve-stems of both 125 valves so as to cause them to work in unison, a valve located upon the inner end of the water-outlet, a float adapted to float upon the water and not the oil, said float being guided so as to come in contact with the last-named valve and close the same by its weight, as 130 specified.

4. In a device of the character described, a

tank, inlet and outlet water-pipes arranged in the lower end of said tank, an oil-outlet pipe extending from the upper end of said tank, a float-valve adapted to control the out-flow of the water-outlet pipe, a float guided vertically within the tank, said float being of such specific gravity as to float upon water and not oil, said float adapted to contact with the float-valve in the water-outlet and close

the same when said float is at its lowest position, as specified.

In testimony whereof I have hereunto affixed my signature in the presence of two subscribing witnesses.

ALBERT C. FRIESEKE.
